UNITED STATES PATENT OFFICE.

RICHARD P. McCULLY, OF BROOKLYN, NEW YORK.

DESIGN FOR A FINGER-SLIDE AND WIRE-HOLDER FOR SURGICAL SNARES.

SPECIFICATION forming part of Design No. 34,313, dated April 2, 1901.

Application filed March 9, 1901. Serial No. 50,525. Term of patent 3½ years.

To all whom it may concern.

Be it known that I, RICHARD P. McCULLY, a citizen of the United States, residing at Brooklyn, Kings county, New York, have invented and produced a new and original Design for a Finger-Slide and Wire-Holder for Surgical Snares, of which the following is a full, clear, and exact description.

My invention relates to a new and original design for a finger-slide and wire-holder for surgical snares.

In the drawings, Figure 1 is a side elevation of my design. Fig. 2 is a section of Fig. 1 on the line X X.

My design consists, primarily, of two rings A A', which are united by a tubular piece B. Projecting from the central upper portion of

the ring A is a threaded post C. A thumb-nut D is mounted upon the post C. The post C has a small hole E located adjacent the edge of the nut D.

The leading feature of my design is the arrangement of the two rings joined by the tubular piece, one of the rings having a threaded post and nut and said post having a small opening therein.

What I claim is—

The design for a finger-slide and wire-holder for surgical snares, substantially as herein shown and described.

RICHARD P. McCULLY.
